UNITED STATES PATENT OFFICE

146,328

DESIGN FOR A FIGURINE

Claude O. Van Denburg, Cleveland, Ohio

Application February 25, 1946, Serial No. 126,894

Term of patent 3½ years

(Cl. D29—23)

To all whom it may concern:

Be it known that I, Claude O. Van Denburg, a citizen of the United States, residing at Cleveland, in the county of Cuyahoga and State of Ohio, have invented a new, original, and ornamental Design for Figurine, of which the following is a specification, reference being had to the accompanying drawing, forming a part thereof.

In the drawing:

Figure 1 is a front elevational view of a figurine, showing my new design;

Figure 2 is a side elevational view thereof; and
Figure 3 is a rear elevational view thereof.

I claim:

The ornamental design for a figurine, substantially as shown.

CLAUDE O. VAN DENBURG.
